SALT SHAKER OR THE LIKE

George J. Strauss, Los Angeles, Calif.

Application April 21, 1959, Serial No. 55,600

Term of patent 14 years

(Cl. D44—22)

FIG. 1.

FIG. 2.

FIG. 3.

Fig. 1 is a perspective view showing a salt shaker or the like, embodying my new design;
Fig. 2 is a side elevational view of the same;
Fig. 3 is a top plan view of the same.

I claim:

The ornamental design for a salt shaker or the like, substantially as shown.
